PROPELLION MEANS

Steve Kiss, Miami, Fla., assignor of one-half to
Julius J. Samson, Miami, Fla.

Application November 19, 1934, Serial No. 753,762

2 Claims. (Cl. 170—156)

This invention appertains to new and useful improvements in propellers of the screw type.

The principal object of the present invention is to provide a propeller of the screw type having spirally disposed blades mounted on a revolving shell and which can be employed for use on either air or marine vessels.

Another important object of the invention is to provide a propeller of the spiral blade type, constructed in such manner as to promote smoothness in operation and relief of a considerable amount of the strain which normally exists on the drive shaft and propeller blades of conventional type propulsion mechanisms.

Another important object of the invention is to provide a propeller constructed in such a manner as to permit ready demountability for the purpose of repair or replacement of parts.

These and various other important objects and advantages of the invention will become apparent to the reader of the following specification.

In the drawings:—

Figure 1 represents a side elevational view of the propeller shown applied to the nose portion of an aircraft.

Figure 2 represents a vertical sectional view taken substantially on line 2—2 of Figure 1.

Figure 3 represents a side elevational view of the shell.

Figure 4 represents a front elevational view of the nose cap.

Figure 5 represents a fragmentary longitudinal sectional view through the drive and driven shafts mounting.

Figure 6 represents an enlarged vertical sectional view taken substantially on the line 6—6 of Figure 5.

Figure 7 represents an enlarged fragmentary detailed sectional view taken substantially on line 7—7 of Figure 5.

Figure 8 represents an enlarged fragmentary detailed sectional view transversely through the propeller blade and adjacent portion of the supporting shell.

Referring to the drawings wherein like numerals designate like parts, it will be seen in Figure 1 that 5 represents the fuselage of an aircraft of the monoplane type having a forwardly reduced nose portion 6 of substantially conical construction, through which the elongated tube 7 (see Figure 5) extends. This tube 7 is fixed axially within the nose 6 by struts 8, each end of the tube 7 being provided with a removable

header 9 between which and the adjacent roller bearing mount 10 a packing element 11 is placed.

The drive shaft which is connected by the universal joint 12 to the usual crank shaft of the engine (not shown) is denoted by the numeral 13 and extends through the rear header 9 into the tube 7 to terminate within the hollow head 14 of the driven shaft 15.

The last-mentioned end of the drive shaft 13 has a reduced portion 16 extending into the pocket 17 where it is supported by the roller bearing mount 18. Adjacent the roller bearings 18 are the roller members 19 which are interposed between the drive shaft 13 and the inner side of the enlargement 14 as clearly shown in Figure 7. A ring 20 is threaded over a portion of the enlarged end 14 of the driven shaft 15 and is flanged as at 21 circumferentially to hold the packing 22 in place and prevent displacement of the aforementioned roller members 19.

As can be clearly seen in Figure 6, these roller members 19 ride against the periphery of the drive shaft 13 and are carried by the cam-shaped pocket 23 at the inner side of the head 14 of the driven shaft 15. In this manner a free-wheeling clutch is afforded which will permit the propeller to rotate independently of the engine and drive shaft 13.

The drive shaft 13 has a thrust collar 24 for engaging the rear roller mount 10, while the forward end portion of the driven shaft 15 is provided with a reduced extension 25 defining a shoulder 26 which abuts the forward roller bearing mount 10. Interposed between the roller bearing mount 27 which supports the rear end portion of the driven shaft 15, and the head 14 of the shaft 15 is a ball bearing thrust mount 28.

The propeller proper includes a bullet-shaped shell 29 through the bore 30 in the reduced end 40 of which extends the reduced portion 25 of the driven shaft 15. The shell 29 is provided with spirally disposed slot-ways 31, leaving spirally disposed bridge members A, each of which is provided with an out-turned flange B at one longitudinal edge and an inturned flange C at its opposite longitudinal edge, the spirally disposed blade 32 being riveted at their inner longitudinal edges to the out-turned flange B as at 33.

The numeral 34 represents the conical-shaped 50 cap member for the forward end of the shell 29, this cap 34 being provided with openings 35 through which the securing elements, such as rivets, can be disposed for securing the same to the reduced end portion of the shell 29. The 55

cap 34 is provided with spirally disposed flanges 36 to which the forward end extensions of the blade 32 can be secured. The cap 34 is provided with a hub 37 which is provided with a key slot 38 at its inner side which can be meshed with a key slot on the reduced portion 25 of the driven shaft and keyed to positively connect the driven shaft 15 with the cap 34, to the end that the cap 34 will rotate the shell 29 which carries the propeller blade 32.

Obviously, a propeller constructed in accordance with the foregoing specification will be more desirable than the elongated outstanding screw type propeller which in operation imparts considerable vibration to the craft. This vibration is scarcely noticeable in a craft equipped with the propulsion means herein described.

Obviously, when two of these propellers are employed in juxtaposition, they are constructed with the blades disposed in opposite spiral direction, so that any tendency of the craft as regards deviation will be neutralized.

While the foregoing specification sets forth the invention in specific terms, it is to be understood that numerous changes in the shape, size and

materials may be resorted to without departing from the spirit and scope of the invention as claimed hereinafter.

What is claimed is:—

1. A propeller comprising an elongated forwardly tapering shell, a conical-shaped cap for the reduced end of the shell, drive means connected to the cap, spirally disposed flanges on the shell, flanges on the said cap aligned with the spiral flanges on the shell, and blades secured to the flanges on the shell, said blades being extended forwardly and connected to the flanges on the cap. 5

1. A propeller comprising an elongated forwardly tapering shell, a conical-shaped cap for the reduced end of the shell, drive means connected to the cap, spirally disposed flanges on the shell, flanges on the said cap aligned with the spiral flanges on the shell, and blades secured to the flanges on the shell, said blades being extended forwardly and connected to the flanges on the cap, 15 said shell being provided with slots following the contour of the said blades. 10
